MECHANISM FOR DISCHARGING CONTENTS
OF RECEPTACLES

Augustine Davis, Jr., Cincinnati, Ohio

Application July 24, 1935, Serial No. 32,917

12 Claims. (Cl. 221—74)

This invention relates to improvements in dispensing mechanism and has particular reference to a mechanism for discharging the contents of receptacles in measured quantities.

One of the principal objects of the present invention is the provision of a mechanism for dispensing lubricating oil into the crank case of engines and for dispensing liquid into containers and for measuring the amount of liquid thereby dispensed.

Another object of this invention is the provision of a mechanism which can be readily applied to existing containers and which in the case of lubricating oil as utilized in gasoline engines will prevent the filling of said containers with an inferior grade of lubricant.

A further object of this invention is the provision of a container for lubricating oil or other fluid which can be filled at the bulk plant and shipped to points of use where the lubricating oil or other liquid is dispensed in measured quantities direct from the container without first emptying said container into a second container from which the oil or fluid is then measured.

Another object of the invention is the provision of a container adapted to have the liquid contents thereof forcibly discharged therefrom and being merely controlled by a dispensing valve and which discharge is measured as same flows through the valve.

Other objects and advantages of the present invention should be readily apparent by reference to the following specification considered in conjunction with the accompanying drawings forming a part thereof, and it is to be understood that any modifications may be made in the exact structural details there shown and described, within the scope of the appended claims, without departing from or exceeding the spirit of the invention.

In the drawings:

Fig. 1 is an elevational view of the improved dispenser of this invention set up and ready for use;

Fig. 2 is an elevational view of the container as shipped from the bulk plant to the point of use;

Fig. 3 is a plan view of the dial of a meter as employed in connection with the dispenser;

Fig. 4 is an enlarged fragmentary vertical sectional view through the container showing the operative parts therein;

Fig. 5 is a sectional view as seen from line 5—5 on Fig. 4, said parts being shown in elevation;

Fig. 6 is a sectional view as seen from line 6—6 on Fig. 4;

Fig. 7 is a modified construction of this invention showing an additional valve which may be employed to prevent gravity discharge from the feed pipe; and

Fig. 8 is a transverse sectional view taken on line 8—8 of Fig. 7.

Throughout the several views of the drawings similar reference characters are employed to denote the same or similar parts.

In the field of engine lubrication, particularly as applied to gasoline motors, dishonesty has been practiced to a large extent in that inferior grades of lubricant have been dispensed from containers of well-known and first grade lubricants. In order to overcome this practice lubricating oil companies and refineries have resorted to the practice of placing their lubricating oil in non-refillable containers; that is, containers that must be practically destroyed before the contents can be obtained. Other companies have utilized special containers or drums into which lubricating oil is dumped and from which it is dispensed through pumps and the like. In the case of the individual sealed destructible containers there is the added expense of the container, while in the case of the drums from which the oil is pumped there is a drainage loss of oil in being transferred from the shipping container to the dispensing container.

By the present invention the difficulty of having an inferior grade of lubricant placed in the container, the added expense of small individual containers and the loss due to transferring the lubricant from the shipping container to the dispensing container are all eliminated. By the present invention the lubricating oil is placed in a container which at once becomes the shipping and dispensing container, since all that is necessary at the point of use is the application thereto of a discharge nozzle and an air line to supply the pressure necessary for lifting the lubricating oil. After the container has been emptied it is returned to the bulk plant and again filled with the same grade or quality of lubricating oil, and then again shipped to the point of use.

Specifically, this invention comprises a receptacle here shown as a can 10 having a body portion 11, a base or bottom 12, a conical top 13 and a neck 14. The said parts are respectively welded or otherwise secured to one another as is well known. In order to add strength to the can to withstand the necessary pressure to be introduced therein, the said body 11 and conical top 13

are corrugated as illustrated in Figs. 1 and 2. The upper end of the neck 14 is provided with a radial flange 15 in turn having internal threads 16 provided thereon. Meshing with the threads 16 are corresponding threads formed exteriorly of a depending flange 17 integral with a cap 18. A suitable gasket 19 is securely clamped between the neck flange 15 and cap 18 to render the tank air-tight when placed in use. The cap 18 has 10 upstanding therefrom a boss 20 provided on its upper end with screw threads 21. Projecting laterally from the boss 20 is a lug 22 having formed therein a bore 23, the outer end of which is threaded to receive a pipe, nipple or the like 24. The bore 23 connects with a bore 25 formed at right angles thereto and communicating with the interior of the can through a one-way check valve housing 26. The check valve housing 26 contains a suitable ball check valve 27 which permits of communication from the outside to the interior of the can but prevents any reverse flow of fluid.

The bottom 12 of the can or receptacle 11 is provided with a depressed portion 28 which constitutes the sump for the container. Disposed within the depression 28 is an annular member 29 having a cavity 30 therein and a radial flange 31 overlying the cavity 30. Formed in the upper surface of the flange 31 is a groove 32 and a plurality of ports 33 connecting the groove 32 with the cavity 30.

The annular member 29 is secured through its radial flange 31 with the collar 34 of a valve casing 35. The valve casing 35 comprises the collar 34 from which rises a sleeve 36 having projecting from the upper end thereof arms 37 shown in Fig. 6 as three in number to provide spaces 38 between adjacent arms. The valve casing collar 34 is additionally provided with a bore 39 therethrough which bore is surrounded by a valve seat 40. Disposed within the bore 39 is a valve member comprising wings 41, shown in dotted lines in Fig. 5, and having a circular boss 42 at the upper end thereof. Pressed or otherwise secured on the boss 42 is a valve member 43 which may conveniently take the form of a rubber or fiber disk to cooperate with the valve seat 40 to close communication through the bore 39. Contacting with the upper surface of the valve seat 43 is a plate 44 having integral therewith a spring boss 45 opposed to a similar boss 46 depending from the valve cage arms 37. The bosses 45 and 46 act as spring retainers and respectively enter opposite ends of an expansion coiled spring 47 which tends to urge the valve 43 to its seat 40.

The valve cage 35 together with the parts carried thereby is soldered, welded or otherwise secured as at 48 to the lower end of a tube or pipe 49 which has its upper end disposed in a counterbore 50 formed in the cap member 20. The upper end of the said pipe or tube 50 is also soldered, welded, or otherwise secured as at 51 to the said cap member 20. The pipe or tube 49 is the feed pipe through which the liquid content of the can 10 is forced by the compressed air acting thereon as will later be made clear, and the said pipe or tube extends substantially the full length of the can or container; that is, 70 from the top to the bottom thereof.

Disposed within the upper end of the pipe or tube 49 is a second pipe or tube 52 which is likewise utilized as a part of the feed pipe as it extends above the pipe or tube 49 and connects same with the filling hose and valve control nozzle as will later on be explained.

The short pipe or tube 52, similar to the feed pipe or tube 49, encircles at its lower end a valve casing 53 and is soldered or otherwise secured on a collar 54 integral with said casing 53. The collar 54 is provided therethrough with a bore 55 surrounded by its upper end by a valve seat 56. Additionally the collar 54 has projecting upwardly therefrom a sleeve 57 from the upper end of which projects arms 58 similar in all respects to the 10 construction of the valve casing 35. Disposed within the bore 55 of the collar 54 is the valve which includes arms 59 and circular boss 60 on which is pressed the valve member 61. This valve member 61 is, similar to the valve member 43, a ring formed of rubber or fiber and adapted to closely engage the valve seat 56 to prevent any flow through the bore 55. Disposed on the upper side of the valve member 43 is a spring plate 62 having rising therefrom the spring boss 63 opposed to a similar boss 64 depending from the under surface of the cage arms 58. The bosses 63 and 64 similar to the bosses 45 and 46 act as spring retainers and respectively enter the upper and lower ends of expansion coiled spring 65 for holding said spring in position, which acts to normally seat the valve member 61.

The upper end of the short feed pipe or tube 52 is soldered, welded or otherwise secured as at 66 to the lower end of an elbow 67. The 30 elbow 67 has its one end 68 threaded and with its axis angularly related to the end to which the tube or pipe 52 is secured. Intermediate its ends the elbow 67 is provided with an annular flange or collar 69 which rests on the upper end 35 of the cap boss 20. A coupling nut 70 surrounds the elbow 67 and has its radial flange 71 engaging with the elbow flange 69 and meshes with the threads 21 of the cap boss 20 for forcing the elbow flange 69 into seating engagement with 40 the end of the cap boss 20.

Encircling the main discharge pipe or tube 49 is a hollow metallic float 89 to the lower end of which is cemented or otherwise secured a valve member 90 which may be formed of rubber, fiber or any other suitable material. The lower surface 91 of the valve member 90 is adapted to seat on the upper surface 92 of the annular member 29 within the sump 28. This float 89 and its valve 90 naturally ride on the upper surface of the fluid in the can or container 10 and when said fluid has been substantially completely exhausted from the can or tank the surfaces 91 and 92 contact one another to close further communication through the ports 33 as will be described in detail later.

As seen in Fig. 1 the nipple 24 projecting from the cap lug 22 is connected with a pipe 72 which has its other end connected with a source of pressure such as an air-compressing pump, air pressure tank, or the like. Disposed in this line 72 is a pressure reducing valve 73 and a shut-off valve 74; the valve 73 being provided to prevent the operator from injecting too much pressure within the tank or container 11, since this container is naturally limited as to the maximum amount of pressure it can stand and since a relatively low amount of pressure is all that is necessary to raise the contents thereof. It will be appreciated that the line 72 may in reality 70 be a flexible hose having a quickly detachable coupling 72' between the end thereof and the nipple 24. From this it will be seen that air pressure may be readily introduced into the tank or container 11.

The upper angular end 68 of the elbow 67 is connected through a suitable coupling nut or the like 75 with a flow meter 76. The flow meter 76 may be of any well-known or desired construction so long as it registers the amount of liquid flowing from the can or container 10. As seen in Fig. 3 this flow meter 76 is provided with a dial 77 graduated at 78 preferably in units of pints and half-pints which cooperate with a pointer 79 for indicating accurately even small quantities of the fluid passing from the can or container 10. In addition the flow meter 76 has a totalizer 80 for indicating the total amount of fluid that has passed therethrough in any given time, the totalizer adding the flow therethrough even after successive cans have been attached thereto, as will be more fully explained later.

The flow meter 76 is provided with an outlet 81 to which one end of the discharge conduit 82 is secured. The other end of the discharge conduit has connected therewith a valve-controlled nozzle 83 actuated by the operator through the handle 84 associated with said nozzle. Intermediate the ends of the conduit 82 a sight glass 85 is disposed which will show that the conduit 82 is filled with the fluid from the can or tank prior to the actuation of the nozzle handle 84. The nozzle 83 is provided at its end adjacent the conduit 82 with a check valve to prevent draining of said conduit by gravity as is sometimes usual with nozzles of this type.

As will be seen from Fig. 4 the upper end of the cap boss 20 is relieved of any threads so as to provide a flange 86 with an undercut groove 87 therebeneath. The purpose for this construction is to permit the crimping thereon of a tearable seal 88 which is applied to the can after same has been filled at the bulk plant and prior to shipment thereof to the place of use.

40 The method of dispensing fluids or liquids, and particularly lubricating oil, and the operation of the improved mechanism is as follows:

The cans or containers 10 have removed therefrom the cap 18 which carries with it the main feed pipe or tube 49 and all parts carried thereby. The cans or containers are then filled with liquid and the cap 18 and parts carried thereby screwed home with the gasket 19 therebetween to form an air-tight joint between the parts. The seal 88 is then applied and the can or container shipped to the point of use which in the case of lubricating oil is a service station, garage or the like. At this point the tube 52 together with parts carried thereby and including the meter 76, discharge hose or conduit 82 and filling nozzle 83 are secured to the cap 20. The nipple 24 is then connected with a source of pressure to fill the can or container with preferably compressed air to the extent of 50 lbs. to the square inch although this amount of pressure is not absolutely necessary as it will all depend on the type of material from which the can or container 10 is made and the construction thereof as to the amount of pressure which it will sustain.

65 After the can has been conditioned as above, the pressure source is disconnected therefrom whereupon the check valve 21 prevents any loss of pressure. It is contemplated, particularly in the case of lubricating oil, that the cans or containers 10 will be mounted on dollies or trucks for carting to the machine to be serviced, whereupon the spout 93 of the filling nozzle 83 is inserted into the engine opening and the handle 84 of the nozzle actuated to release the lubricant therethrough.

75 It should be noted that the valve mechanism

carried respectively by the valve cages 35 and 53 act as foot valves or check valves to prevent the flow of lubricant or other fluid from their respective feed pipes back into the can or container 10. From this it will follow that once these pipes 6 are filled they will remain so but are readily opened by the fluid under the pressure applied thereto. In actual use there would be a separate short filling tube or pipe 52, valve mechanism associated with the valve cage 53, elbow assembly 10 67, meter 76, discharge hose or conduit 82 and filling nozzle 83 for each different type or grade of lubricating oil or different kind of fluid used. These parts would remain filled after their initial filling and while being transferred from one can 15 or container 10 to the next due to the emptying of preceding cans. By this arrangement the sight glass 85 is always filled and the user and customer can be readily apprised of the fact that he is getting lubricant or other fluid and not air 20 each time the filling nozzle is opened.

In order to further insure that no air is discharged through the filling nozzle the float valve assembly 89-90 immediately closes further communication between the can or container 10 and the feed pipes 49 and 52 when the last available oil or other fluid reaches the sump.

After the can or container has been emptied a small cap is screwed onto the threads 21 and the can or container returned to the bulk plant for 30 filling with the same kind of fluid previously therein, or the same grade of lubricating oil. Since, and as was above pointed out, the user will use the same short discharge tube or pipe 52 and the parts carried thereby for the same 35 grade or type of fluid and lubricating oil there is no danger of a mixture of different kinds of fluids or lubricants.

In the modification shown in Figs. 7 and 8 the main feed pipe 49 is severed at a point just below 40 the foot valve of the second or short feed pipe 52 and at this point a second valve inserted in this pipe. This second valve is utilized to prevent the pouring or dumping of the fluid from the feed pipe 49 after the can or container 10 has been 45 exhausted and at the same time this valve provides a mechanism whereby the air pressure may be placed on the contents of the can or container at the bulk plant instead of placing said pressure thereon at the point of use or service station. 50

Specifically, this modified construction comprises feed pipe sections 49a and 49b each shouldered and welded or otherwise secured respectively at 94 and 95 to the opposite ends of a collar 96 of a valve cage 97. The valve cage 97 is constructed similar to the cages 35 and 53 in that it has projecting from the collar 96 a sleeve 98 from one end of which extend arms 99 having depending therefrom a spring boss 100. The spring boss 100 is opposed to a second spring boss 101 and 60 each is inserted in the opposite end of an expansion coil spring 102. The boss 101 is integral with a valve member 103 adapted to seat on the collar 96 and close a port 104 therethrough.

In order to open the valve 103 it is so positioned 65 with respect to the foot valve of the short feed pipe 52 as to be opened thereby and for this reason the collar 96 is provided with several apertures or openings 105 through which pass pins 106 projecting from the valve member 103. 70

The operation of this modified mechanism is believed readily understood since it is only necessary to telescope the short feed pipe 52 within the main feed pipe 51 in order to have the pins 106 engage with the collar 54 of the said feed 75

pipe 51 foot valve mechanism to unseat the valve 103 thereby establishing communication between the feed pipes 49 and 52. At the same time as soon as the short feed pipe 52 is removed from 5 the main feed pipe the valve 103 immediately seats thereby preventing any further or inadvertent discharge from the feed pipe 49.

With the structure disclosed and described in Fig. 4 after the short feed pipe has been properly 10 positioned and the air pressure applied thereto the said feed pipe cannot be removed so long as there is air on the liquid in the can 10 without spilling or discharging said liquid, while with the structure in Fig. 7 these parts may be dis- 15 assembled at any time because the pressure within the can 10 and on the content thereof will immediately seat the valve 103 and thereby seal the said opening. Furthermore, with the construction of Fig. 4 after the float valve mecha- 20 nism 89-90 has been seated the can or container may be upset and the liquid in the feed pipe 49 drained therefrom, while with the structure of Fig. 7 this is prohibited.

It is believed that from the foregoing the im- 25 proved method of dispersing lubricating oil and the operation of the improved dispenser will be fully understood.

What is claimed is:

1. In a mechanism of the class described the 30 combination of a container having a feed pipe therein, means for introducing pressure within the container for forcing the contents of the container through the feed pipe, a second feed pipe adapted to be inserted within the first feed pipe 35 and to receive fluid from said first feed pipe, and a spring-controlled foot valve at the lower end of each feed pipe for preventing reverse gravity flow therethrough.

2. In a mechanism of the class described the 40 combination of a container having a feed pipe therein, means for introducing pressure within the container for forcing the contents of the container through the feed pipe, a second feed pipe adapted to be inserted within the first feed pipe 45 and to receive fluid from said first feed pipe, a spring-controlled foot valve at the lower end of each feed pipe for preventing reverse gravity flow therethrough, an intake at the lower end of the first feed pipe, and a float-actuated valve for closing 50 said intake upon exhaustion of the contents of the container.

3. In a mechanism of the class described the 55 combination of a container, means for introducing a pressure within said container, a pair of telescoping feed pipes one associated permanently with the container, a metering mechanism associated with the second feed pipe, a manually operable control valve beyond the metering mechanism for controlling the flow of the liquid content of the container through the telescoping feed pipes, and a valve associated with one of said feed pipes to prevent flow therethrough in a feeding direction and operable upon telescoping of said feed pipes to open same and thereby 65 permit the said feed flow.

4. In a mechanism of the class described the 70 combination of a sealed container for liquids adapted to have introduced therein a pressure force, a first feed pipe within said container, a pair of valves in said feed pipe operable to prevent flow from the said feed pipe from opposite ends thereof, a second feed pipe adapted to be telescoped within the first feed pipe, a valve in said second feed pipe preventing flow in one direction relative thereto, and means associated 75

with said second feed pipe operable upon telescoping with the first feed pipe for opening one of the valves thereof to effect flow therethrough.

5. In a mechanism of the class described the 5 combination of a sealed container for liquids adapted to have introduced therein a pressure force, a first feed pipe within said container, a pair of valves in said feed pipe operable to prevent flow from the said feed pipe from opposite ends thereof, a second feed pipe adapted to be 10 telescoped within the first feed pipe, a valve in said second feed pipe preventing flow in one direction relative thereto, means associated with said second feed pipe operable upon telescoping with the first feed pipe for opening one of the 15 valves thereof to effect flow therethrough, and an auxiliary valve operable upon exhaustion of the fluid content of the container for closing communication between the container and feed pipes.

6. In a mechanism of the class described for 20 discharging lubricating oil and the like the combination of a container having a relatively small neck at one end thereof through which the container is filled, a bottom for said container, a sump formed in said bottom, a cap for closing 25 the neck of the container and having an airtight joint therebetween, a feed pipe depending from the cap to the bottom of the container, an intake member on the lower end of the feed pipe and substantially filling the sump, said intake 30 member having ports whereby communication is established between the container, sump and interior of the feed pipe, a valve normally closing communication between the feed pipe and container and sump, and a one-way pressure port 35 through the container cap whereby air pressure may be introduced into the container to force the content thereof through the feed pipe after unseating the valve therein.

7. In a mechanism of the class described for 40 discharging lubricating oil and the like the combination of a container having a relatively small neck at one end thereof through which the container is filled, a bottom for said container, a sump formed in said bottom, a cap for closing the 45 neck of the container and having an air-tight joint therebetween, a feed pipe depending from the cap to the bottom of the container, an intake member on the lower end of the feed pipe and substantially filling the sump, said intake member having ports whereby communication is 50 established between the container, sump and interior of the feed pipe, a valve normally closing communication between the feed pipe and container and sump, a one-way pressure port 55 through the container cap whereby air pressure may be introduced into the container to force the content thereof through the feed pipe after unseating the valve therein, and a float valve within said container for closing the ports in the 60 intake member upon exhaustion of the contents of the container.

8. In a mechanism of the class described for 65 discharging lubricating oil and the like the combination of a container having a relatively small neck at one end thereof through which the container is filled, a bottom for said container, a sump formed in said bottom, a cap for closing the neck of the container and having an airtight joint therebetween, a feed pipe depending from 70 the cap to the bottom of the container, an intake member on the lower end of the feed pipe and substantially filling the sump, said intake member having ports whereby communication is 75 established between the container, sump and in-

terior of the feed pipe, a valve normally closing communication between the feed pipe and container and sump, a one-way pressure port through the container cap whereby air pressure 5 may be introduced into the container to force the content thereof through the feed pipe after unseating the valve therein, a second feed pipe adapted to be telescoped within the cap feed pipe, means for securing the second feed pipe in operative position, and a manually controlled valve associated with the second feed pipe to control the flow through the said feed pipes.

9. In a mechanism of the class described the combination of a container having a filling neck, a cap for closing said neck after the filling of the container, a discharge pipe depending from the cap within the container, a pair of valves in said pipe and operable to prevent flow through said pipe in either direction, additional discharge 20 means insertable in said discharge pipe, and means associated with the additional discharge means for unseating one of said valves whereby flow in a discharging direction may be effected, and said discharging means beyond the discharge 25 pipe including a metering device and a manually controlled discharge nozzle beyond said metering device.

10. In a mechanism of the class described the combination with a refillable portable container 30 having a filling neck, and a cap for closing said filling neck and which cap and neck have an air-tight joint between them, a discharge pipe depending from said cap into the container to a point adjacent the bottom thereof, a one-way 35 check valve associated with said pipe whereby the container may be discharged therethrough but not charged, a one-way pressure port through said cap through which pressure is introduced into the container for unseating the check valve and discharging the contents of the container 40 through the discharge pipe, of a removable discharge mechanism adapted to be connected with the discharge pipe for receiving fluid from said pipe and including means for controlling and directing the discharge through the pipe.

45 11. In a mechanism of the class described the combination with a refillable portable container having a filling neck, a cap for closing said filling neck and which cap and neck have an air-

tight joint between them, a discharge pipe depending from said cap into the container to a point adjacent the bottom thereof, a one-way check valve associated with said pipe whereby the container may be discharged therethrough 5 but not charged, a one-way pressure port through said cap through which pressure is introduced into the container for unseating the check valve and discharging the contents of the container through the discharge pipe, of a removable discharge 10 mechanism adapted to be connected with the discharge pipe for receiving fluid from said pipe and controllably directing the discharge through the pipe, including a second discharge pipe, means for connecting same with the 15 cap in telescoping relation with the first discharge pipe, a metering device, and a manually controlled discharge conduit from said metering device.

12. In a mechanism of the class described the combination with a refillable container having a filling neck, and a cap for closing said filling neck and which cap and neck have an air-tight joint between them, of a discharge pipe depending from said cap into the container to a point adjacent the bottom thereof, a one-way check valve 20 associated with said pipe whereby the container may be discharged therethrough but not charged, a one-way pressure port through said cap through which pressure is introduced into the 25 container for unseating the check valve and discharging the contents of the container through the discharge pipe, a removable discharge mechanism adapted to be connected with the discharge pipe for receiving fluid from said pipe and controllably directing the discharge through the 30 pipe, including a second discharge pipe, means for connecting same with the cap in telescoping relation with the first discharge pipe, a metering device, a manually controlled discharge conduit 35 from said metering device, and a one-way check valve in said second discharge pipe to prevent gravity flow through said pipe, metering device and discharge conduit, but operable to permit discharge through these parts by the pressure 40 actuated fluid passing through the first discharge pipe.

AUGUSTINE DAVIS, JR.
